UNITED STATES PATENT OFFICE.

CARL E. WENZEL, OF NEWARK, NEW JERSEY.

DETONATING TOY.

SPECIFICATION forming part of Letters Patent No. 729,985, dated June 2, 1903.

Application filed November 13, 1902. Serial No. 131,142. (No model.)

To all whom it may concern:

Be it known that I, CARL E. WENZEL, a citizen of the United States, residing at Newark, in the county of Essex and State of New Jersey, have invented and produced a new and original Improvement in Detonating Toys; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 The objects of this invention are to provide a detonating toy adapted to automatically feed across its anvil a tape or connected series of explosive caps, to thus enable a rapid succession of reports to be fired, to provide 20 a hammer adapted to sever said explosive-tape as it descends upon the anvil, to secure a simple and durable construction, and to obtain other advantages and results, some of which will be referred to hereinafter in connection with the description of the working parts.

The invention consists in the improved detonating toy and in the arrangements and combinations of parts of the same, all substantially as will be hereinafter set forth and finally embraced in the clauses of the claim.

Referring to the accompanying drawings, in which like numerals of reference indicate corresponding parts in each of the several figures, Figure 1 is a side view of my improved toy with the nearer side plate of the frame partially broken away to disclose the parts more fully. Fig. 2 is a front end view of the toy, and Fig. 3 is a rear end view.

In said drawings, 2 indicates a carriage or frame supporting a cannon 3, the whole being preferably cast in two longitudinal halves with the joint or division-line extending 45 lengthwise of the cannon. At the rear end of the cannon is a hammer 4, pivoted at its lower end upon a rod 5, extending across the lower part of the frame and serving as a brace therefor. A spring 6 normally holds said 50 hammer in forward position with its head against the cannon, and an operating-lever 7, fulcrumed at its lower end upon a screw 8 in

one side plate of the frame 2, is provided at its inner side with transverse recesses or grooves 9 10, adapted to receive the end of a 55 finger 11, projecting laterally from the hammer. The lower groove is inclined at its bottom forwardly, and thus adapted to pass the finger end from behind, but to carry the hammer with it on a backward swing until said 60 finger sliding on the lever arrives at the upper groove 11, through which it escapes for a forward throw, all as described in detail in my prior application, Serial No. 128,364, filed 65 October 22, 1902.

In the present invention an anvil 12 is formed at the upper part of the rear end of the cannon, and just below said anvil is attached by lateral ears 13 the upper end of a tape guide or passage-way 14, which extends 70 downwardly forward beneath the cannon to near the plane of the lower edges of the side plates of the frame 2. Said tape-guide is preferably formed of sheet metal rolled up into a somewhat flattened tube adapted to 75 loosely receive the tape and being longitudinally open or slotted, as at 15, along its front side.

The hammer 4 at its point of pivoting upon the rod 5 is extended laterally to form a hub 16, from the ends of which arms 17 17 extend forwardly and upwardly on opposite sides of the tape-guide 14. Between the forward ends of said arms 17 extends a bar 18, lying in front of the tape-guide, and upon this bar is 80 pivoted an arm 19, which extends upwardly rearward and lies at its free end in the slot 15 of the said tape-guide. A spiral spring 20, coiled on the bar 18, bears at one end upon the said arm 19 to normally hold it in said 85 slot, and said arm is at its extremity pointed or otherwise adapted to engage the tape or strip of caps.

In operation, the hammer 4 being drawn back or away from the anvil 12, a strip of 9 caps is slid up through the guide 14 until its upper end projects in proper position. The hammer is then released and explodes said cap, the feeding-arm 19 at the same time slipping idly down over the tape. When the hammer is again retracted, the feeding-arm 19 engages the cap-strip or tape and pushes it upward to expose another cap, the several parts of the mechanism being proportioned

to move the said tape in accordance with the distance between the caps or explosive deposits.

The forward striking end of the hammer 4 is recessed or cut away at its lower part, as at 21, to clear the top of the tape-guide 14, and at the lower edge of the striking face 22 is a transverse rib 23, adapted to sever the upper projecting end of the cap-tape simultaneously with its explosion, and said rib 23 preferably fits into a recess or groove 24 on the anvil for obvious reasons.

The lower end of the tape-guide 14 is preferably enlarged or flared, as at 25, to facilitate the entrance of a strip of caps, and said lower end is in the present drawings shown held in place by a cross-piece 26, extending from side to side of the frame 2.

Having thus described the invention, what I claim as new is—

1. In a detonating toy having an anvil and a hammer pivoted below said anvil of a cap strip or tape guide leading upwardly rearward to said anvil and lying in front of said hammer, a rigid arm extending from said hammer past said tape-guide, and a finger pivoted on said arm and being adapted to feed a strip of caps along said guide.

2. In a detonating toy having an anvil and a hammer pivoted below said anvil, of a cap strip or tape guide leading upwardly rearward to said anvil and lying in front of said hammer, rigid arms extending from opposite ends of the pivotal hub of said hammer forwardly on opposite sides of the tape-guide, a cross-bar supported by said arms in front of the tape-guide, and a tape-feeding finger pivoted on said bar and being adapted to en-

gage at its free end a cap-tape lying in said guide.

3. In a detonating toy, an anvil, a flattened tubular tape-guide extending downwardly forward from said anvil and being slotted at its front side, a hammer pivoted back of said tape-guide and below the anvil and having an arm extending forwardly from its fulcrum pivot past the tape-guide, and a tape-feeding finger pivotally supported by said arm and having its free end normally lying in the slot of the tape-guide.

4. A detonating toy having a substantially vertical anvil, a flattened tubular tape-guide extending downward away from said anvil and being longitudinally slotted, a hammer at the rear of said tape-guide, and a pivoted tape-feeding finger having a free end lying in said slotted tape-guide and being connected to said hammer to be operated thereby.

5. The combination of a frame comprising opposite upright side pieces, a cannon supported on said frame and presenting at its rear a vertical anvil, a tape-guide leading from the lower edge of said anvil downward between said side pieces of the frame, a hammer between said side pieces at the rear of said tape-guide, and a tape-feeding finger connected to said hammer and projecting into said tape-guide.

In testimony that I claim the foregoing I have hereunto set my hand this 5th day of November, 1902.

CARL E. WENZEL.
